UNITED STATES PATENT OFFICE.

RHODES LOCKWOOD, OF CHARLESTOWN, MASSACHUSETTS.

ATOMIZER.

SPECIFICATION forming part of Letters Patent No. 251,720, dated January 3, 1882.

Application filed July 2, 1881. (Model.)

To all whom it may concern:

Be it known that I, RHODES LOCKWOOD, of Charlestown, county of Suffolk, State of Massachusetts, have invented an Improvement in 5 Atomizers, of which the following description, in connection with the accompanying drawing, is a specification.

My invention relates to atomizers, and has for its object to so construct an atomizer that 10 it can be readily cleaned, and to make the nozzle adjustable, so that the spray may issue in any direction therefrom as is needed when used in connection with the nasal or throat passages for medical or other purposes.

15 The invention is embodied in an atomizer in which the liquid-passage is located within the air-tube, and the said air-tube is provided with a detachable tip containing an orifice directed across the orifice of the liquid-tube in the usual 20 manner, the said tip being also provided with a passage, through which the jet-piece of the liquid-tube passes. The said jet-piece is provided with a shoulder which engages a seat upon the inside of the said tip, to thus maintain the extreme point or orifice of the liquid-jet piece in the same position relative to the orifice of the air-passage, and to prevent escape 25 of air from the air-tube around the liquid-jet pieces. The said tip is adapted to be rotated 30 upon the end of the air tube or passage, so that the current of air from its orifice may cross the liquid-orifice and throw the spray therefrom in any desired direction. As herein shown, the 35 said tip is connected with the end of the air-tube by screw-threads, so that in turning it to change the direction of the spray a slight longitudinal movement is produced upon the said tube, and the liquid-tube is made yielding, so that in this longitudinal movement its jet-piece 40 will always remain in engagement with the inside of the said tip, and in the same relative position thereto.

The drawing shows, in vertical section, an atomizer constructed in accordance with my 45 invention.

The stopper-piece *a*, provided with a bushing, *b*, of cork or other suitable material to enter the neck of the liquid-reservoir *c*, is provided with the usual fine air-inlet passage, 2, 50 and has connected with it at its upper end the main air-tube *d*, preferably bent at an angle to the axis of the reservoir *c*, for convenience

in applying the spray at any desired point. The said stopper-piece *a* has a longitudinal passage, *d'*, through it in continuation of the 55 air-tube *d*, into which the air enters through the passage 3 from the usual forcing apparatus, *e*.

The liquid-pipe *f* is placed concentrically within the air tube and passage *d d'*, and the 60 suction-pipe *f'* is fitted upon the outside of the passage *f* and inside of the passage *d'*, thus closing the latter and forming a continuation of the liquid-passage *f* and maintaining the 65 said liquid-passage in proper position with the air-passage.

At the end of the liquid-passage *f* is a jet-piece, *g*, fitted therein and having the fine passage and orifice necessary to produce a proper 70 atomizing action.

The air-tube *d* is provided with a tip, *h*, (shown as screwed thereon,) and provided with an orifice, *i*, directed across the end of the jet-piece *g*, which passes through an opening, 4, in the said tip *h*, provided with a tapering seat 75 at 5, to receive a corresponding shoulder upon the jet-piece *g*, which thus tightly closes the passage 4, preventing the escape of air there-through around the jet-piece *g*. By turning the tip *h* its orifice *i* can be brought in any desired 80 angular position relative to the jet-piece *j*, so as to throw the spray in any desired direction, it being shown in full lines in proper position to throw it down, as when used for treating the throat-passages, and in dotted 85 lines to throw the spray upward. Owing to the curve in the pipes *d f* and the elasticity of the latter the shoulder of the jet-piece *g* will remain in engagement with the seat 5 in the tip *h* when the latter is turned for about a single revolution on its screw-threads to vary the 90 direction of the jet of spray, and the mouths of the orifices *g* and *i* will be retained in the proper relation. When the tip *h* is removed by unscrewing it the jet-piece *g* can be withdrawn from the end of the pipe *f* and the sediment, which naturally collects at the inner end, 95

6, of the said jet-piece, can be readily removed from the pipe *f*, which is of uniform bore throughout, and the jet-piece itself may be 100 readily cleared by passing a wire through it, in case the particles have collected within its passage. If, however, the said jet-piece were made undetachable from the pipe *f*, as is now com-

- monly practiced, it would be very difficult and almost impossible to dislodge the sediment collected at the point where the passage contracts to form the orifice, as at 6, since inserting a 5 wire through the said orifice would merely dislodge the particles temporarily so that they would remain in the end of the pipe f near the orifice ready to clog it as soon as the atomizer is again operated.
- 10 I am aware that an atomizer has been made provided with a single removable tip containing both the air and liquid orifices, and al- that an independent removable tip has been used for the air-passage in an atomizing appa- 15 ratus in which the liquid-passage is continuous to its orifice, which is undetachable.

I claim—

1. The air-tube and its tip free to be rotated thereon, the said tip being provided with an air- 20 orifice and central opening, combined with the liquid-tube and its jet-piece passing through the said central opening, substantially as and for the purpose described.

2. The air-tube and its tip free to be rotated thereon, the said tip being provided with an 25 air-orifice and central opening and seat, com- bined with the liquid-tube and its jet-piece passing through the said central opening, and provided with a shoulder to engage the said seat, substantially as and for the purpose de- 30 scribed.

3. In an atomizer, the air and liquid tubes, combined with a removable tip for the air-tube and an independent loosely-connected removable jet-piece for the liquid-tube, of smaller 35 bore than the said tube and inserted therein, and an air-forcing apparatus to force air through the said air-tube and its tip, substantially as and for the purpose described.

In testimony whereof I have signed my name 40 to this specification in the presence of two sub- scribing witnesses.

RHODES LOCKWOOD.
